CLAIM

The ornamental design for a tape cartridge for a label printer, as shown and described.

DESCRIPTION

FIG. 1 is a front, bottom, and right side perspective view of a first embodiment of a tape cartridge for a label printer showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a front, bottom, and right side perspective view of a second embodiment of a tape cartridge for a label printer showing my new design;

FIG. 9 is a front elevational view thereof;

FIG. 10 is a rear elevational view thereof;

FIG. 11 is a top plan view thereof;

FIG. 12 is a bottom plan view thereof;

FIG. 13 is a right side elevational view thereof; and,

FIG. 14 is a left side elevational view thereof.

The features shown in broken lines in the drawings depict environmental subject matter only and form no part of the claimed design. The dash-dotted lines denote the boundary of the claim and form no part of the claimed design. The solid black areas in the drawing are black in color.
